ATTORNEY

UNITED STATES PATENT OFFICE.

GERTRUDE WHITSON, OF LOS ANGELES, CALIFORNIA.

COMPOSITE PICTURE.

Application filed December 24, 1927. Serial No. 242,391.

My invention relates to a type of so-called butterfly picture being more particularly a silhouette picture having a colored background made from the natural wings of butterflies.

It is an object of my invention to combine the varied coloring and shading which is present in butterflies' wings with a black or other suitably colored silhouette image to give a varied lighting effect and to present a finished picture having a highly colored background changeable in shade and effect according to change of viewpoint and embracing a foreground object in relief against such background.

Other objects of my invention will be better understood from the following description of an illustrated embodiment of same as shown in the accompanying drawings and in which:

Fig. 1 is a view illustrating a finished picture embodying the use of my invention.

Fig. 2 is a sectional view along the line 2—2 of Fig. 1.

Fig. 3 is a view corresponding to Fig. 1 but in which the mat and the silhouette image have not been placed in position.

Fig. 4 is a view illustrating a type of silhouette image used in the production of pictures as herein illustrated.

More particularly describing my invention, the numeral 11 indicates a back board which is surrounded by a frame 12. A plurality of butterflies' wings indicated at 13 are placed upon the back board 12 to give any desired background effect such as the sky indicated at 14; the body of water at 15; the horizon at 16 and if desired, clouds or a moon as indicated at 17 and 18. It will be understood that through the use of variously colored wings any desired background effect may be easily obtained to set the foreground image out in relief.

The numeral 20 indicates the foreground silhouette image cut from black paper or any other suitable substance to form a pleasing combination with the background. The silhouette image 20 is placed upon the butterflies' wings indicated at 15 in a position as somewhat shown in Fig. 1 and a suitably prepared mat 21 is placed over the combination

to hold the same in place upon the back board 11.

The mat may be covered by a glass face as indicated at 22 and I find that the most pleasing color effects are obtained by making the mat and the silhouette of the same material, the preference in most cases being a black card board or paper. For the purpose of holding the backboard 11 in firm engagement with the mat 21, I provide a packing member 23 which may be composed of felt or other suitable substance and is placed in the frame 12 between the backboard 11 and a frame backing 24.

By making a composite picture as above described it is immediately apparent that striking effects may be produced as the contrast between the foreground silhouette and the background of changeable colored butterflies' wings is marked. The silhouette having thickness adds to the attractiveness of the effect produced, as when viewed the object formed or pictured by the silhouette stands out in relief against the background.

My invention is not to be confused with pictures formed by cutting out the object to be represented from a sheet of material and forming such object by the use of butterflies' wings or other highly colored material, but consists essentially in forming a background of butterflies' wings over and in front of which is placed the subject of the picture.

I have found it desirable although not entirely necessary to apply paste to the back board for receiving the wings and holding the same in place and also paste may be applied between the wings and silhouette for the purpose of keeping the silhouette in place.

While I have herein described and illustrated a single embodiment of my invention, it will be understood that various modifications of the same might be easily made by those familiar with the art without in the least departing from the spirit or scope of my invention as described above and in the following claims.

I claim as my invention:

1. A composite picture comprising: a frame; a back plate mounted in said frame; butterfly wings placed on said back plate; a mat having an opening therein placed upon

said back plate with said opening over said butterfly wings; and a silhouette image mounted in said opening over said butterfly wings.

5. 2. A composite picture comprising a background composed of butterfly wings; a backing for said background; a silhouette image

placed before said background; and a mat surrounding said image and holding said butterfly wings in position on said backing. 10

In testimony whereof, I have hereunto set my hand at Los Angeles, California, this 12th day of December, 1927.

GERTRUDE WHITSON.
